J. H. VENHOFF

FASTENING DEVICE

Filed Nov. 20, 1922

Inventor
John H. Venhoff

By Maya A. Schmidt
Attorney

UNITED STATES PATENT OFFICE.

JOHN H. VENHOFF, OF LOUISVILLE, KENTUCKY.

FASTENING DEVICE.

Application filed November 20, 1922. Serial No. 602,077.

To all whom it may concern:

Be it known that I, JOHN H. VENHOFF, a citizen of the United States, residing at Louisville, in the county of Jefferson and 5 State of Kentucky, have invented certain new and useful Improvements in Fastening Devices, of which the following is a specification.

This invention relates to devices for effecting 10 an adjustable connection between strap ends, and its object is to provide a simple, efficient and easily adjusted device of this kind.

The object stated is attained by means of 15 a novel combination and arrangement of parts to be hereinafter described and claimed, and in order that the same may be better understood, reference is had to the accompanying drawing, wherein—

20 Figure 1 is a side elevation of a cap showing the application of the invention thereto; Fig. 2 is an elevation of the device; Fig. 3 is an edge view thereof, and

25 Fig. 4 is a cross-section on the line 4—4 of Fig. 3.

The device has been designed more particularly for application to caps and similar head-coverings to permit adjustment thereof to different sized heads. It is, however, 30 to be understood that the device is capable of various other uses.

In the drawing, 5 denotes a cloth or other cap having a peak or vizor 6 provided with the usual fasteners, such as a snap button 7 35 and a cooperating socket member 8. In order that the cap may be adjusted to fit heads of different sizes, there is secured to each side a strap. These straps are shown at 9 and 10, respectively, and they extend 40 around to the front of the cap where they are adjustably connected by the fastening device which is the subject matter of the present application for patent. The preferred embodiment of the invention has been 45 shown, but it will be understood that various changes and modifications may be made without a departure from the spirit and scope of the invention as claimed herein-after.

50 The fastening device comprises two members, one of which is connected to the free end of the strap 9, and the other to the free end of the strap 10.

The member which is connected to the strap 9 consists of a metallic plate 11 having 55 a central and longitudinally extending bead 12 provided with a series of longitudinally spaced and transversely extending slits 13. The plate 11 is secured to the strap end by means of lateral end tongues 14 which are 60 bent over the strap edges and clinched into the strap from the back thereof.

The member which is attached to the strap 10 consists of a plate 15 shaped similar to the plate 11 and adapted to be positioned 65 beneath or back of the latter plate in slideable contact therewith, its bead 16 fitting in the channel in the plate 11 formed by its bead 12. The plate 15 is secured to the strap 10 by tongues 17 in the same manner 70 the plate 11 is secured to the strap 9. The adjustable connection between the plates 11 and 15 is made by a bail carried by the latter and selectively engageable with the cross-slits 13 of the former. 75

The bail is composed of side bars 17 and a cross-bar 18 connecting the same at one end. At their other ends, the side bars 17 have rearward bends 19 terminating in inward lateral bends 20 which are resilient to 80 frictionally engage the under side of the plate 15. The side edges of the plate 15 have notches 21 in which the bends 19 seat, and said bends have outward offsets to form shoulders at 22, said shoulders seating on 85 the face of the plate. The plate 15 is thus gripped between the parts 20 and 22, and in this manner the bail is firmly secured to said plate, it being prevented from sliding along the same by the notches 21. 90

The side bars 17 of the bail are resilient and have a normal tendency to swing toward the face of the plate 15, and hence if the cross bar 18 is placed in one of the slits 13 it will be securely held therein, and at the 95 same time, it can be readily pried up for replacement in some other slit if the adjustment is to be changed. The interlocking beads 12 and 16 serve as guides for the plates 11 and 15 in their sliding movement, 100 and they also prevent lateral displacement of the plates relative to each other.

I claim:

A fastening device comprising a pair of plates slidably connected relative to each 105 other, and a bail carried by one of the plates,

said plate having edge notches, and the other plate having holding means for the bail, said bail consisting of side members and a cross-member connecting the same at one end, 5 the side members being resilient and having rearwardly presented end portions which pass through the aforesaid edge notches and

have inward resilient bends engaging the back of the notched plate, and said end portions having lateral offsets forming shoulders which engage the face of the notched plate. 10

In testimony whereof I affix my signature.
JOHN H. VENHOFF.
